UNITED STATES PATENT OFFICE.

GLENN MORE, OF JAMESTOWN, NEW YORK, ASSIGNOR TO THE BLACKSTONE MANUFACTURING COMPANY, OF JAMESTOWN, NEW YORK, A CORPORATION OF NEW YORK.

OPERATING-GEARING FOR WASHING-MACHINES.

1,252,924.

Specification of Letters Patent.

Patented Jan. 8, 1918.

Application filed January 19, 1917. Serial No. 143,832.

To all whom it may concern:

Be it known that I, GLENN MORE, a citizen of the United States, and a resident of Jamestown, in the county of Chautauqua and State of New York, have invented certain new and useful Improvements in Operating-Gearing for Washing-Machines; and I do hereby declare that the following is a full, clear, and exact description thereof, reference being had to the accompanying drawings, and to the letters of reference marked thereon, which form a part of this specification.

This invention relates to improvements in gearing for operating washing machines and the like, and consists of the matters hereinafter described and more particularly set forth in the appended claims.

The object of the invention is to provide a power driven gearing for washing machines of the well known dolly type, which is simple in construction, efficient and powerful in operation, and capable of easy attachment to the tub body providing the support for the gearing.

The many advantages of the invention will be made apparent as I proceed with my specification.

In the drawings:

Figure 1 is a view representing a top plan of a washing machine with my improved gearing applied thereto, for operating the dolly shaft.

Fig. 2 is a transverse, vertical sectional view through the same, the plane of the section being indicated by the line 2-2 of Fig. 1.

Fig. 3 is a vertical sectional view on an enlarged scale, the plane of the section being indicated by the line 3-3 of Fig. 1.

Referring now to that embodiment of my invention illustrated in the drawings:—10 indicates the tub body of a washing machine, which is of familiar construction and has the usual cover comprising a fixed part or top 11 and a hinged part or lid 12. 15 indicates the upright dolly shaft which is carried by the hinged lid and depends into the tub in the usual manner.

14 indicates a bracket plate which is attached to the top of the lid 12 and has a

vertical bearing sleeve 14^a arranged at the center of the tub for the dolly shaft 13. The bracket plate 14 has upright, laterally spaced, inclined arms 15, 15^a which extend 55 into a plane above the fixed top 11 and are adapted to be connected to similarly disposed upright arms 16, 16^a, which rise from a second bracket plate 17 attached to the fixed top 11 of the tub. The arm 15^a has a 60 reduced end part 18, which engages in a suitable hole or aperture formed in the associated or adjacent arm 16^a. A short horizontal shaft 19 extends through suitable holes in the arms 15 and 16 in line with the 65 end part 18, said shaft 19 and end part 18 providing the pintle of the hinge connection between the tub lid 12 and the fixed top 11 of the tub.

A bevel gear or pinion 20, fixed to the top 70 end of the dolly shaft 13, is engaged by a segmental bevel gear 21, which is mounted to oscillate on a shaft 22 journaled in upright bearing lugs 22^a formed on the bracket plate 14 near the bearing sleeve 14^a. A 75 worm gear 23 is rotatively mounted on said horizontal shaft 19, adjacent the arm 16 of the bracket 17. A worm 24 engages the worm gear 23, on its bottom side. Said worm 24 is arranged in a pocket or depression 80 formed in the bracket plate 17 and is fixed to the armature shaft of a motor 31, which shaft has bearing in flanges or ribs 25, 25 placed at each end of said pocket.

The oscillating, segmental gear 21 is operatively connected to the worm gear 23 by a link 26 having pivotal connection at one end, to a crank pin 27 on the segmental gear, and having a like connection at the other end, to a crank pin 28 on said worm 85 gear 23. The link 26 is bent, and the crank pin 28 is made of such length that the link may pass the end of the shaft 19, which provides bearing for the worm gear 23.

The bracket plate 17 has a depending web 95 29 which hangs down alongside the tub body 10, and said web has a laterally extending shelf 30 adapted to support the motor 31, said motor being attached thereto in any suitable manner.

The operation of the gearing will be apparent from the foregoing description. The

rapid rotation of the motor armature shaft is communicated and reduced through the worm 24 and the worm gear 23, to the link 26 which imparts an oscillating, back and forth movement to the segmental gear 21. This in turn, through the gear 20, imparts the required alternating, rotary movement to the dolly shaft. As the axis of the hinged connection between the lid and the fixed top of the tub is in line with the central axis of the worm gear 23, it is apparent that the tub lid may be swung into an open position without binding, blocking, or in any other way interfering with the proper relative arrangement of the parts of the gearing. By arranging the motor on the shelf 30, which is located in a plane below the fixed top 11 and the hinged lid 12, the said lid may be raised to the desired full open position without being interfered with by said motor. By locating the worm 24 in the depression 25, and causing it to mesh with the gear 23 on its under side, said worm is amply protected against accidental engagement with the person or clothing of the operator.

The gearing and its supporting brackets are compact in arrangement, and may be easily assembled.

While in describing my invention, I have referred to certain details of construction and arrangement of parts, I do not wish to be limited thereto except as may be set forth in the appended claims.

I claim as my invention:

1. In a gearing, in combination with a main support and an auxiliary support hinged thereto, a bracket plate adapted to be attached to said auxiliary support, an upright operating shaft, a pinion fixed to said shaft, an oscillating, segmental gear mounted on said bracket plate and engaged with said pinion, a second bracket plate adapted for attachment to said main support adjacent said auxiliary support, said bracket plates having arms hinged together, a worm gear rotatively mounted on said second bracket plate with its axis in line with the hinged axis of said arms, a link connecting said worm gear with said segmental gear, a worm carried by said bracket plate and engaged with said worm gear, and a power driven prime mover supported by said second bracket plate and having its shaft operatively connected to said worm.

2. In a gearing, in combination with a main support and an auxiliary support hinged thereto, a bracket plate adapted to be attached to said auxiliary support, an upright operating shaft journaled in said bracket plate, a second bracket plate adapted for attachment to said main support adjacent said auxiliary support, said bracket plates having arms hinged together, a worm

gear rotatively mounted on said second bracket plate with its axis in line with the hinged axis of said arms, means operatively connecting said worm gear to said operating shaft for imparting an alternating rotary movement thereto, a worm having bearing in said bracket plate and engaged with said worm gear, and a power driven prime mover supported by said second bracket plate and having its shaft operatively connected to said worm.

3. In a gearing, in combination with a main support and an auxiliary support hinged thereto, a bracket plate adapted to be attached to said auxiliary support, an upright operating shaft journaled in said bracket plate, a second bracket plate adapted for attachment to said main support adjacent said auxiliary support, said bracket plates having arms hinged together, a worm gear rotatively mounted on said second bracket plate with its axis in line with the hinged axis of said arms, means operatively connecting said worm gear with said operating shaft for imparting an alternating rotary movement thereto, and a power driven prime mover supported by said bracket plate and having its shaft journaled in bearing members on said bracket plate, and a worm fixed to said prime mover shaft and operatively engaged with said worm.

4. In a gearing, in combination with a main support and an auxiliary support hinged thereto, a bracket plate adapted to be attached to said auxiliary support, an upright operating shaft journaled in said bracket plate, a pinion fixed to said shaft, an oscillating, segmental gear mounted on said bracket plate and engaged with said pinion, a second bracket plate adapted for attachment to said main support adjacent said auxiliary support, said bracket plates having pairs of arms hinged together, a shaft operatively connecting one pair of said arms together in line with the hinged axis of the other pair of said arms, a worm gear rotatively mounted on said shaft, a crank pin on said worm gear, a link connecting said crank pin with said segmental gear, a power driven shaft having bearing in said second bracket plate below said worm gear, and a worm fixed to said shaft and operatively engaged with said worm gear.

5. In a gearing, in combination with a main support and an auxiliary support hinged thereto, a bracket plate adapted to be attached to said auxiliary support, an upright operating shaft journaled in said bracket plate, a pinion fixed to said shaft, an oscillating, segmental gear mounted on said bracket plate and engaged with said pinion, a second bracket plate adapted for attachment to said main support adjacent said auxiliary support, said bracket plates

having pairs of arms hinged together, a worm gear rotatively mounted on said second bracket plate with its axis in line with the hinged axis of said arms, a link operatively connecting said worm gear and said segmental gear, a worm having bearing in said bracket plate, and engaged with said worm gear, the bracket plate on said main support having a shelf arranged in a plane 10 at one side of and below that of the body

part of said bracket, and a motor supported on said shelf and driving said worm.

In testimony, that I claim the foregoing as my invention I affix my signature in the presence of two witnesses, this 11th day of 15
January A. D. 1917.

GLENN MORE.
